UNITED STATES PATENT OFFICE.

WILLIAM APPENBRINK, OF QUINCY, ILLINOIS.

FLUE-SCRAPER.

No. 922,999.

Specification of Letters Patent.

Patented May 25, 1909.

Application filed March 2, 1909. Serial No. 480,994.

To all whom it may concern:

Be it known that I, WILLIAM APPENBRINK, a citizen of the United States, resident of Quincy, in the county of Adams and State of Illinois, have made a certain new and useful Invention in Flue-Scrapers; and I declare the following to be a full, clear, and exact description of the same, such as will enable others skilled in the art to which it appertains to make and use the invention, reference being had to the accompanying drawings, and to letters or figures of reference marked thereon, which form a part of this specification.

Figure 1 is a side view of the invention. Fig. 2 is a central longitudinal section of the same, the blades being partly broken away. Fig. 3 is a detail perspective view of one of the scraper blades. Fig. 4 is a section on the line 4—4, Fig. 2.

The invention relates to flue scrapers and consists in the novel construction and combinations of parts as hereinafter set forth.

In the accompanying drawings illustrating the invention the letter *a*, designates the central rotary shaft having screw threaded portions at its forward end, as shown at *b* and *c*. Screwed upon the forwardmost threaded portion *b*, is a hexagonal nut or head *d*. Any desired number of lateral faces *e*, may be provided upon this prismatic head or nut.

f, f', represent the spiral ribbon-form spring-metal cleaner blades, in number corresponding to the number of lateral faces of the nut *d*, said blades having plane outer end portions *f', f'*, lying adjacent to the plane lateral faces of the nut, and terminating in short right-angle bends *f²*, *f²*, lying adjacent to the forward end face of the nut. The opposite end portions of the blades are reduced or cut away as shown at *f³*. These cleaner or scraper blades are assembled with the end portions *f', f'*, thereof against the lateral faces of the nut *d*, and the right angle terminations *f²*, *f²*, thereof against the forward end face of said nut, when the hollow sleeve *g*, having an internal diameter slightly greater than the diameter of the nut *d*, is slipped over the same and over the forward end portions of the blades, the end wall *g'* of said sleeve forcing the right angle terminations of the blades against the end face of the nut and securely holding the blades in position, the interval *h*, between the lateral faces of the nut and the inner peripheral surface of the sleeve being at the same time sufficient to allow a

limited radial movement of the cleaner blades. The hollow sleeve is loosely engaged with the shaft by means of a perforation *g²*, in its end wall *g'*, a securing nut *i*, engaging the threaded portion *b*, of the shaft, being employed to force the sleeve against the nut and hold the cleaner blades in position.

Each blade *f*, has a helical turn through one right angle plus the angle subtended by a lateral face *e*, of the nut *d*, or ninety degrees plus sixty degrees in the case of a hexagonal prism, as is the nut in the present case, making a total turn of each blade of one hundred and fifty degrees, as shown. This turn is accomplished mainly in the first two thirds of the length of the blade from the prismatic head or nut, the last third of the length of the blade being mainly in a substantially radial or axial plane.

For the purpose of limiting the radial movement of the cleaner blades, a rear head *k*, has screw-threaded engagement with the threaded portion *c*, of the central shaft and is provided with slots *l*, at its forward end, arranged, each in an axial plane, radial with respect to the shaft, and perpendicular to the lateral faces of the forward head or nut *d*, each slot *l*, being opposite a lateral face *e*, and receiving a reduced end portion *f³*, of a cleaner blade.

This flue cleaner is of simple construction, being composed of a minimum number of simple parts, and no auxiliary springs are required therein, as the cleaner blades are themselves formed of ribbon-form strips of spring metal.

In the operation of the invention the forward end portions of the cleaner blades, which are in a substantially radial or axial plane with respect to the central shaft, are in the rotation of such shaft, thrown radially outward by centrifugal force against the interior of the flue to be cleaned. This throw of the blades is limited by the bore of the incrusted flue, such throw becoming greater as the scale is gradually scraped away, and being further and finally limited by the outer end walls of the slots of the rear head *k*. The diameter of the scraper formed by the cleaner blades taken as a whole gradually increases from front to rear.

Having thus described my invention, what I claim as new and desire to secure by Letters Patent is—

1. A flue cleaner having a central shaft, a

forward prismatic head, a rear head having radial slots and helically twisted cleaner blades of ribbon form, having flat forward end portions secured to the lateral faces of the prismatic head, and radially movable rear end portions, having each an axial radial relation with respect to said shaft and engaging a slot of the rear head, said blades having their main twist in about the first two thirds 10 of their length from their flat forward end portions.

2. A flue cleaner having a central shaft, a forward prismatic head, a rear head having radial slots in axial alinement with the prismatic faces of the forward head, and helically twisted cleaner blades, having each, a twist 15 of one right angle plus the angle subtended by a lateral face of the prismatic head, said blades having flat forward end portions, each 20 in a plane at right angles to the radius of the shaft and secured to a face of the forward head, and radially movable rear end portions, having each an axial radial relation

with respect to said shaft and engaging the radial slots of the rear head. 25

3. A flue cleaner having a central shaft, a forward prismatic head, a rear head having radial slots, a hollow sleeve surrounding the prismatic head and having an end wall separated from an end wall of the head by an interval, and helically twisted cleaner blades having flat forward end portions lying adjacent to the lateral faces of the prismatic head between the same and said sleeve, and having right angle terminations located in said 30 interval, said blades having radially movable rear end portions having each an axial radial relation to said shaft and engaging a slot of the rear head. 35

In testimony whereof I affix my signature, 40 in presence of two witnesses.

WILLIAM APPENBRINK.
